UNITED STATES PATENT OFFICE.

ROY A. McCARTY, OF WILKINSBURG, PENNSYLVANIA, ASSIGNEE TO WESTINGHOUSE ELECTRIC & MANUFACTURING COMPANY, A CORPORATION OF PENNSYLVANIA.

DAMPER WINDING.

Application filed November 5, 1923. Serial No. 672,834.

To all whom it may concern:

Be it known that I, Roy A. McCARTY, a citizen of the United States, and a resident of Wilkinsburg, in the county of Allegheny and State of Pennsylvania, have invented a new and useful Improvement in Damper Windings, of which the following is a specification.

My invention relates to dynamo-electric machines and it has special reference to salient-pole, alternating-current machines provided with short-circuited damper windings or starting windings.

One object of my invention is to provide a machine of the above-described character having a rotating field member provided with an improved cage winding which shall be of an electrically efficient and mechanically strong construction and which shall permit the disassembly of the rotor without destroying or damaging the damper winding.

Another object of my invention is to provide a damper winding for machines of the above-described character comprising a plurality of integral groups of damping conductors and detachable, unitary short-circuiting members for effecting a short-circuiting connection between the individual groups.

A still further object of my invention is to so support the damper winding upon the rotor as to secure the same against excessive strains imposed thereon by centrifugal force, while providing also a large radiating surface for dissipating the heat generated in the winding.

The damper windings of synchronous machines, while in themselves simple and not complicated elements of the machines, must conform to certain very definite requirements in order to perform satisfactorily the functions for which they are designed. The electrical resistance of the winding must, for certain conditions, be low and the heat-radiating surface must be sufficient to dissipate the heat generated in the windings by the damping currents flowing therein. Since the centrifugal force exerted upon the winding, especially in cases of high speed machines, may assume large values, particular care must be taken also to avoid the addition of unnecessary weight to the winding and to make the same mechanically strong.

It is also desirable that the salient pole members of such machines shall be easily detached and disassembled without destroying or seriously damaging the damper winding. In prior structures, it has been proposed to secure the conducting damper bars, which are embedded in the pole faces of the polar projections, to short-circuiting rings on both sides of the rotor, by means of screw bolts. Such constructions are not very desirable since, on account of the size of the conductor, the screw bolts are necessarily small in diameter and give thus only a small degree of mechanical security, while adding unnecessarily to the weight of the winding and consequently, to the centrifugal forces exerted thereupon.

I have found that the performance of the damper winding may be, considerably improved mechanically and electrically, without sacrificing any advantages in respect to the ease of disassembly of the rotor. To this end I provide for each pole member, a separate damping group consisting of individual conductors embedded in the pole face and a pair of short-circuiting segments which are welded or brazed to the conductors on both sides thereof. Each damping group thus constitutes an integral damping element of high conductivity and of a mechanically strong structure. The individual damping groups are short-circuited by means of specially constructed unitary short-circuiting rings which are clamped thereto by means of a relatively small number of easily detachable screws, thus permitting the disassembly of the rotor without the destruction of the winding.

With the foregoing and other objects in view, my invention consists of the arrangements and details of construction herein-after described and claimed and illustrated in the accompanying drawing, wherein—

Figure 1 is a view in elevation of a portion of a salient-pole rotor member of a dynamo-electric machine provided with a damper winding constructed in accordance with my invention;

Fig. 2 is a sectional view of a pole member illustrated in Fig. 1 taken along the line II—II thereof; and

Figs. 3 and 4 are similar views illustrating modifications of my invention.

In Figs. 1 and 2 is shown a rotating field member of a dynamo-electric machine, com-

prising a central body member or yoke 1 to which are secured a plurality of polar projections 2 comprising iron laminations 3 assembled and held together between two end plates 4 and mounted in the yoke 1 by means of dovetail projections 5 and corresponding dovetail grooves 6 in the yoke. Exciting field coils 7 are mounted upon the pole pieces and may be removed therefrom upon detaching the pole piece from the yoke. The pole faces of the laminated polar projections are provided with axially-extending, partially closed slots 9, in which are embedded conductor members 10 projecting beyond both ends of the slots. It will be noted that the upper portions of the end plates 4 are provided with fingers 11 for holding and clamping together the slotted part of the laminations.

20 Short-circuiting segments 12, of angular cross-section, are provided on both sides of each polar projection and have shoulders 13 bearing against projecting portions 14 of the end plates 4 in such manner as to support the damper structure and at the same time allow for expansion of the damper bars 10 when they are heated. The outer peripheral surfaces 15 of the short-circuiting segments are so arranged as to be aligned 25 with the under surfaces of the projecting damping conductors 10. The conductors 10 are welded or brazed to the short-circuiting segments at their contacting surface 15 and thus constitute a unitary structure of high-conductivity which is self-supporting without the need of additional fastening bolts.

30 A short-circuiting ring 16 is mounted within the cylindrical space which is bounded by the angular short-circuiting segments 12, the cross section of the ring being substantially rectangular and fitting into the rectangular space enclosed between the two arms of the angular short-circuiting segments. The ring makes contact with the 35 entire inner surface 17 of the short-circuiting segments, thereby assuring a perfect and reliable electrical contact. The rings 16 are furthermore clamped by means of bolts 18 to the individual segments and constitute the short-circuiting connection between the segments, thus completing the damper winding.

40 By means of my construction, the individual damping groups and the damping winding as a whole, have a maximum of conductivity and, therefore, a maximum of effectiveness, which is obtained without the use of an excessive number of bolts and, at the same time, the readily detachable short-circuiting rings 16 do not interfere with the disassembly of the rotor member. By means of my construction, I also obtain a high degree of mechanical strength while providing a maximum radiating surface for dissipating the heat generated in the winding, since most of the surface of the damper-

winding structure is in direct contact with the air and moves in the same.

45 In Fig. 3 is shown a modification of my invention in which the short-circuiting ring 19 is not made solid in cross section, but, instead, is a helically wound copper strap conductor 20. The copper strap preferably has a small thickness and a fairly great depth for increasing its mechanical strength in the direction in which it is exposed to excessive centrifugal forces. The coils or layers of the short-circuiting ring may be riveted or welded together, and I may also provide ventilating spaces 21 between the individual layers by means of spacing washers 22. The short-circuiting ring 19 of Fig. 3 is secured to the short-circuiting segments by means of bolts 18, in the same manner as that in Fig. 2.

50 The above-described construction permits the employment of short-circuiting rings of low resistance, such as rings made of copper, instead of brass, which has been required heretofore on account of its greater mechanical strength. The mechanical strength of the ring 19 is sufficient to withstand the stresses in the unsupported portion between the individual poles, while affording liberal radiating surfaces for dissipating the heat generated in the winding.

55 In Fig. 4 is shown a modification of my invention comprising a somewhat simplified construction which is employed in medium speed machines. The short-circuiting conductors 10 are welded or brazed to short-circuiting segments 23 of angular form. On account of the lower speed at which the construction is operated, I dispense with the shoulders 13 used in the constructions illustrated in Figs. 2 and 3, obtaining thereby 60 a cheaper unit. A metallic ring 24 is clamped to the individual segments 23 by means of bolts 18 and short-circuits the individual damping groups upon the several pole members.

65 My invention is susceptible of various other modifications and changes and I desire, therefore, that only such limitations shall be placed thereupon as are imposed by the prior art or set forth in the appended 70 claims.

75 I claim as my invention:

1. In a dynamo-electric machine, a rotor member comprising a central body portion, a plurality of detachable polar projections secured to said central body portion, axially disposed conductors in the pole faces of said polar projections, a pair of short-circuiting segments for each polar projection, said segments being integrally united with the end portions of said conductors, a pair of continuous annular short-circuiting members disposed on both sides of said rotor respectively, and means for detachably clamping said short-circuiting seg- 80

- ments to said annular short-circuiting members.
2. In a dynamo-electric machine, a rotor member comprising a central body portion, a plurality of detachable polar projections secured to said central body portion, each projection being provided on both sides thereof, with end plates having at their outer ends outwardly projecting lips, short-circuiting segments of angular cross-section for each side of each polar projection, one side of said angular segments being disposed toward said end plates and provided with a projecting member bearing outwardly against said lips, the other side of said segments being in contact with the end portions of said conductors and integrally united thereto for short circuiting the same, unitary continuous short-circuiting rings fitting into the circular spaces bounded by said segments and means for detachably clamping said rings to said segments.
3. In a dynamo-electric machine, a rotor member comprising a central body portion, a plurality of detachable polar projections secured to said central body portion, each projection being provided on both sides thereof, with end plates having at their outer ends outwardly projecting lips, short-circuiting segments of angular cross-section for each side of each polar projection, one side of said angular segments being disposed toward said end plates and secured to the same, the other side of said segments being in contact with the end portions of said conductors and integrally united thereto for short-circuiting the same, unitary short-circuiting rings fitting into the circular spaces bounded by said segments, the cross section of said rings being such as to fit into the angular spaces of said segments and make contact over the entire surface of the same, and detachable means for clamping said rings to said segments.
4. A rotating field member for a dynamo-electric machine, comprising a salient-pole core member, field-magnet coils thereon, the salient pole members having overhanging pole-face members thereon, a damper unit on each salient-pole member comprising conductor bars embedded in the pole-face portion thereof and a short-circuiting segmental member permanently united to the ends of said bars on each end of the salient-pole member, and continuous short-circuiting rings detachably united to the respective short-circuiting members of all of the salient-pole members at each end of said rotating field member.
- In testimony whereof, I have hereunto subscribed my name this 30th day of October 1923.

ROY A. McCARTY.
